METHOD OF MAKING RUBBERY ARTICLES

Alvon R. Cox, Cuyahoga Falls, Ohio, assignor, by
mesne assignments, to The B. F. Goodrich
Company, Akron, Ohio, a corporation of New
York

Application October 11, 1951, Serial No. 250,903

1 Claim. (Cl. 18—58.7)

1

This invention relates to a deposition form and pertains more particularly to a deposition form for making rubbery articles having one or more reinforcing members embedded in the rubbery matrix thereof and the method of making such articles.

It is an object of this invention to provide a form for making rubbery articles.

It is also an object of this invention to provide a deposition form for making rubbery articles having a reinforcing member embedded in the wall thereof.

Another object of this invention is to provide a deposition form to which a reinforcing member may be detachably secured to permit the reinforcing member to be maintained in a desired position with respect to said form during the deposition operation.

Still another object of this invention is to provide a method of embedding a reinforcing member in the wall of a rubbery article made by depositing a layer of rubbery material on the surface of a deposition form.

Other objects of this invention will be apparent from the drawings and description which follow.

Many thin-walled rubbery articles such as gloves, bathing caps, overshoes, toys and the like are made by depositing a rubbery coating from a liquid rubber dispersion on an appropriately shaped form and subsequently vulcanizing the rubbery deposit coated on the form to cause the deposit to permanently maintain the contour of the form after the deposit is "stripped" therefrom. However, in view of the fact that the rubbery articles are relatively flexible, it frequently is desirable to incorporate a reinforcing member in the wall of the article to provide additional rigidity to that portion of the wall. One conventional method of incorporating a reinforcing member in the wall of the article is to deposit a rubbery layer over the form, adhere the reinforcing member to the outer face of the rubbery layer and deposit a second layer of rubbery material over the first deposit and reinforcing member embedding the reinforcing member between the two deposits. The deposits with the reinforcing member embedded therebetween are then vulcanized while still disposed over the form to form an integral wall member and the vulcanized article is then "stripped" from the form, the reinforcing member embedded in the wall of the article providing the additional rigidity desired.

The aforementioned method of incorporating a reinforcing member in the wall of a rubbery

2

article made by depositing the rubbery material on the face of a deposition form is a time-consuming and expensive operation, in that it is necessary that the deposition of the rubbery material on the form comprises a two-step dipping process. Furthermore, in the above-mentioned method of embedding reinforcing members in rubbery articles it is frequently difficult to position the reinforcing member in the exact position desired and often during the second dipping process the reinforcing member becomes dislodged from its desired position rendering the finished article unsatisfactory.

I have invented a deposition form upon which a rubbery article having a reinforcing member embedded therein may be fabricated which attains the objections enumerated above and which is not subjected to the deficiencies inherent in conventional deposition forms. A deposition form within the purview of this invention is provided with securing members to which a reinforcing member may be secured during the deposition or dipping process but from which it may be readily detached after a desired layer of rubbery material has been deposited on the form.

To clearly illustrate this invention reference will henceforth be made to the embodiments of this invention shown in the drawings, however, it will be understood that the embodiments are merely illustrations of the invention and that I do not intend to limit the scope of this invention to these embodiments.

In the drawings:

Fig. 1 is a front elevation view of a deposition form within the purview of this invention for making a thin-walled respiratory mask showing a reinforcing member partly broken away detachably secured thereto;

Fig. 2 is a side elevation view partly broken away and in section of the deposition form of Fig. 1 immersed in a body of latex and showing a rubbery deposit disposed over the surface of the form;

Fig. 3 is a view in section on line 3—3 of Fig. 1, showing a rubbery deposit over the surface of the form;

Fig. 4 is a side elevation view in section of a portion of a deposition form showing another embodiment of this invention and showing a rubbery deposit disposed over the surface of the form; and

Fig. 5 is an elevation view in section of the rubbery deposit shown in Fig. 4 after removal from the form, showing the reinforcing member completely embedded in the rubbery wall.

In one embodiment of this invention, shown

in Figs. 1 and 2, the deposition or dipping form 10 comprises a body member 11 having a surface configuration conforming to the general contour of the rubbery respiratory mask to be fabricated thereon. Body member 11 may be constructed of any material usually employed in making deposition or dipping forms such as porcelain, aluminum, stone, wood, various metals or alloys, and the like, preferably a non-corrodible and light-weight material such as aluminum is used, and may be of a solid or hollow construction.

Grooved securing or supporting members 12, 12 embedded in body member 11 are adapted to firmly grasp and retain an elongated relatively rigid reinforcing member 13 in one desired position, preferably in spaced relationship with respect to body member 11, during the deposition operation, reinforcing member 13 being secured in place merely by frictional engagement thereof in the grooves 14, 14 of securing members 12, 12 as shown in Figs. 1 and 2. Securing members 12, 12 may be secured in the face of body member 11 in any usual manner, such as by casting body member 11 around the preformed securing members 12, 12 or by providing securing members 12, 12 with an appropriate threaded portion to allow them to be screwed into the face of body member 11 which has been previously fabricated.

Form 10 is provided with a supporting arm or extension 15 to allow form 10 to be suspended from an appropriate support (not shown) in a latex bath 16 confined in dipping tank 17.

A preferred method of utilizing form 10 in the manufacture of a thin-walled rubbery respirator mask comprises inserting reinforcing member 13 in grooves 14, 14 of securing members 12, 12 embedded in body member 11, as shown in Fig. 1, dipping form 10 in a rubber coagulant, such as aqueous acetic acid, a solution of calcium nitrate in acetone, etc., and then immersing the coagulant coated form 10 in an aqueous dispersion of a rubber-like material such as rubber latex for a sufficient period of time (1-15 minutes or more) to build up a deposit 18 of rubber solids of the desired thickness over the surface of form 10 and around reinforcing member 13 by diffusion of the coagulant into the latex, reinforcing member 13 being entirely embedded in the rubbery deposit except at those places along which reinforcing member 13 contacts securing members 12, 12. The coated form is heated to dry and/or to vulcanize the rubbery deposit 18. The vulcanized deposit 18 with reinforcing member 13 embedded therein is removed or "stripped" from form 10 and any undesired areas of deposit 18 are cut from the rubbery deposit at this time or just prior to removing the deposit from the form. The un-embedded areas of reinforcing member 13 occurring at the contact areas of reinforcing member 13 with securing members 12, 12 are filled with an appropriate rubbery composition to form a fillet 19 over the exposed areas of reinforcing member 13, as shown in Fig. 5.

In a second embodiment of this invention, as shown in Fig. 4, deposition form 20 is the same as form 10 having a body member 21 and supporting arm or extension 22 except that grooved securing members 12, 12 are replaced with permanent magnetic or electromagnetic securing or supporting members 23. In utilizing form 20, reinforcing member 13 must be constructed of a paramagnetic material such as iron or steel, so that reinforcing member 13 will be magnetically

attracted and firmly held in a desired position with respect to form 20 during the deposition process.

The method of utilizing form 20 may be the same as the method enumerated above in the utilization of form 10.

In manufacturing rubbery articles by depositing a layer of rubber-like material on the surface of a deposition form within the purview of this invention it is possible to incorporate a relatively rigid reinforcing member within the rubbery deposit in a single latex dipping operation, whereas, heretofore, it has been necessary to employ at least a two-stage latex dipping operation to incorporate the reinforcing member in the rubbery deposit. Accordingly, fabricating reinforced rubbery articles in accordance with this invention is less expensive and less time-consuming than if conventional deposition forms are utilized.

Deposition forms within the scope of this invention are adapted to securely maintain a reinforcing member in a desired location on the face of the form during the entire dipping operation to provide a rubbery article which is reinforced along a desired portion of the wall of the article, whereas incorporating a reinforcing member in the wall of the article in the conventional manner frequently results in the reinforcing member becoming displaced during the deposition process from its desired position resulting in an unsatisfactory article.

It is clear that obvious modifications and variations of this invention made be made without departing from the spirit and scope of this invention as defined in the appended claim.

I claim:

The method of making a rubbery article having a reinforcing member embedded therein comprising providing a deposition form including a body member having the general configuration of said article and having means projecting from the face of said body member for detachably engaging said reinforcing member in spaced relationship from the face of said body member, detachably securing said reinforcing member to said means in spaced relation from said body member, depositing a rubbery layer on the face of said deposition form and about said reinforcing member secured thereto by immersing said deposition form with said reinforcing member attached thereto in an aqueous rubbery dispersion, removing said rubbery layer with said reinforcing member embedded therein from said deposition form, and depositing a rubbery composition in the opening in said rubbery layer occasioned by said means to completely embed said reinforcing member in a rubbery matrix.
